[57] **CLAIM**

The ornamental design for a key ring, as shown and described:

DESCRIPTION

FIG. 1 is a top plan view of a key ring showing my new design;

FIG. 2 is a side elevational view thereof; and

FIG. 3 is an enlarged scale perspective view thereof.
In the various figures of the drawing, the various stippling and hatching is intended as surface shading only
and does not connote color.

FIG. 1

FIG. 2

FIG. 3
